UNITED STATES PATENT OFFICE.

HARRY EUGENE KELLEY, OF NIAGARA FALLS, ASSIGNOR TO THE ONEIDA COMMUNITY, (LIMITED,) OF COMMUNITY, NEW YORK.

CHAIN-FASTENER.

SPECIFICATION forming part of Letters Patent No. 404,631, dated June 4, 1889.

Application filed November 28, 1888. Serial No. 292,094. (No model.)

To all whom it may concern:

Be it known that I, HARRY EUGENE KELLEY, of Niagara Falls, in the county of Niagara, in the State of New York, have invented new and useful Improvements in 5 Chain-Fasteners, of which the following, taken in connection with the accompanying drawings, is a full, clear, and exact description.

This invention is a specific improvement of 10 the class of chain-fasteners which have a bar pivoted intermediate of its length to a body-plate attached to the end of a chain or strap.

My present invention consists, essentially, 15 of a chain-fastener composed of a body-plate, a bar pivoted to said body-plate, a stop arranged to arrest the movement of the aforesaid bar in one direction, and a coil-spring holding the bar normally resting on the stop; and the invention also consists in certain 20 novel features of the details of the device, as hereinafter fully described, and specifically set forth in the claims.

In the accompanying drawings, Figure 1 is 25 a plan view of a chain-fastener embodying my invention. Fig. 2 is an edge view of the same. Fig. 3 is a transverse section on line $x\ x$, Fig. 2. Fig. 4 is a transverse section on line $y\ y$, Fig. 1. Figs. 5 and 6 are detached plan views of the coupling-bar and disk to 30 which it is pivoted, and Fig. 7 is a plan view of the blank from which the body-plate is formed.

Similar letters of reference indicate corresponding parts.

35 A denotes the body-plate of the chain-fastener. Said plate I form from a blank stamped out of sheet metal, of the shape shown in Fig. 7 of the drawings, the ends of the blank being of the form of annular heads $t\ t$, each of 40 which has a square or other angular perforation i at the center. This blank I bend at the center of its length, so as to cause the two heads $t\ t$ to stand parallel side by side, and with the perforations $i\ i$ directly opposite each 45 other and form an annular case A'. The central portion of the blank, being narrower than the end portions, forms a loop or link l for attachment to a chain or strap.

In the case A', I pivot the bar B at the center of its length preferably by forming the 50 central portion of the bar with an annular

eye b , and with an elongated notch f in the edge of said eye.

In the eye b , I place an annular disk d , which is formed with a projection e and provided 55 with a square or angular perforation v , corresponding to the perforations $i\ i$ in the heads $t\ t$ of the body-plate A. The projection e of the disk is entered into the notch f aforesaid, and the bar B, with the disk d seated in the 60 eye b , is inserted between the heads $t\ t$, and by means of a square or angular pin p , passing through the perforations $i\ i$ and v , the disk is firmly sustained between the aforesaid heads, and the bar B, turning on said disk, is 65 thus pivoted to the body-plate. The projection e of the disk serves as a stop which limits the movement of the bar B in one direction by coming in contact with the shoulder at one end of the notch f . The bar B is held 70 normally in the aforesaid position by means of a coil-spring h , seated in the eye b and upon the disk d , which is thinner than the bar B, so as to leave room for the reception of the aforesaid spring. One end of this spring is 75 attached to the bar B, and the opposite end is attached to the disk d . The spring is wound in such a direction as to hold the bar normally resting on the stop e .

Having described my invention, what I claim 80 as new, and desire to secure by Letters Patent, is—

1. A chain-fastener consisting of a body-plate, a bar pivoted to the body-plate, a stop arranged to arrest the movement of the aforesaid bar in one direction, and a coiled spring 85 holding the bar normally resting on the stop, as set forth.

2. The improved chain-fastener consisting of a body-plate, a bar pivoted to the body-plate and provided with a chamber at its pivot, a stop in position to arrest the movement of the aforesaid bar in one direction, and a coil-spring seated in the aforesaid chamber and holding the bar normally resting on the 95 stop, as set forth.

3. The combination of the body-plate A, formed with the case A', the bar B, pivoted in said case, a stop arranged to arrest the swinging of the aforesaid bar in one direction, and a coil-spring inclosed in the aforesaid case and holding the bar normally rest- 100

ing on the stop, substantially as described and shown:

4. The combination of the body-plate A, formed with the case A', the disk *d*, confined in the said case and provided with the projection *e*, the bar B, formed with the eye *b*, and pivoted thereby on the aforesaid disk, and provided with the elongated notch *f* for the reception of the projection *e*, and the coil-spring *h*, seated in the eye *b* and connected at opposite ends, respectively, to the bar B

and disk *d*, substantially as described and shown.

In testimony whereof I have hereunto signed my name, in the presence of two witnesses, at Buffalo, in the county of Erie, in the State of New York, this 16th day of November, 1888.

HARRY EUGENE KELLEY. [L. s.]
